UNITED STATES PATENT OFFICE.

JOHN WESLEY FERGUSON, OF BLOOMFIELD, NEW JERSEY.

BRUSH.

No. 823,520.

Specification of Letters Patent.

Patented June 19, 1906.

Application filed April 13, 1905. Serial No. 255,447.

To all whom it may concern:

Be it known that I, JOHN WESLEY FERGUSON, a citizen of the United States, residing at Bloomfield, in the county of Essex and State of New Jersey, have invented certain new and useful Improvements in Brushes; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

15 This invention relates to that class of brushes which are made dustless in their operation by the use of oil or other liquid supplied from a tank or reservoir which is carried upon the brush, and more particularly to that class of said brushes in which the reservoir is separable from the brush proper, so that said brush can be detached at pleasure and different ones employed with the same reservoir and handle for different kinds of work, and so that the brush proper when worn out can be cheaply and easily replaced by the new one without throwing away the oil-reservoir and handle means.

20 The objects of the present improvements are to simplify the construction of the brush, to make the oil-reservoir serve as a permanent brush-back without having an independent piece therefor, to secure an improved attachment of the reservoir to the brush proper, to provide a supply-cap for the reservoir which shall facilitate filling the same, to secure improved means for distributing the oil from the reservoir to the absorbent tufts of the brush, to so regulate and control the 25 said supplying of oil that the said absorbent tufts will not have to be drawn with such exacting care in making the brush, to guard against any possible escape of oil elsewhere than to the absorbent tufts, to provide efficient 30 venting means, and to secure other advantages and results some of which may be hereinafter referred to in connection with the description of the working parts.

35 The invention consists in the improved brush and in the arrangements and combinations of parts of the same, all substantially as will be hereinafter set forth, and finally embraced in the clauses of the claim.

40 Referring to the accompanying drawings, 45 in which like numerals of reference indicate corresponding parts in each of the several fig-

ures, Figure 1 is a side elevation of a brush of my improved construction, partly in central longitudinal section, as upon line *x*, Fig. 3. Fig. 2 is a view of the oil-reservoir from beneath. Figs. 3 and 4 are transverse sections of the brush, taken upon lines *y* and *y'*, respectively, of Fig. 1. Fig. 5 is a central vertical section of a supply-cap for the oil-reservoir, and Fig. 6 illustrates a fastening-bolt 50 for holding the parts of the brush together.

In said drawings, 2 indicates an oil tank or reservoir, preferably formed of sheet metal in a shape adapted to fit the top of the brush proper and being rounded at its upper part to present a pleasing appearance. The floor 55 of said tank projects beyond its walls, as at 4, and is then bent downward at right angles to form a depending flange or skirt 5. Said reservoir is thus adapted to be set upon the top of the brush-block 24, with its said flange or skirt 5 partly inclosing the same, as shown.

A curved bail 6 is adapted to lie transversely across the brush at a point midway of its ends, the extremities 7 of said bail 80 fitting against the opposite vertical sides of the reservoir and brush-back, as shown in Fig. 4. Said ends 7 and the brush-block 24 are then bored transversely, as at 9, to receive a clamping-bolt 10. The ends 7 of the 85 bail 6 bear at their upper portions 11 upon the shoulders 4 of the oil tank or reservoir, so that when the bail 6 is clamped to the brush proper the reservoir is also held firmly in place. A handle of any suitable and ordinary construction (not shown) may then be connected to the bail 6.

The clamping-bolt 10 has at one end a finger-piece 12 and head 13, and its shank 14 is normally cylindrical. Portions of this shank, however, adjacent to the head 13 and at the opposite extremity of the bolt are flattened or recessed, as at 15, where the bolt passes through the bail 6, as shown in Fig. 4. If, therefore, the bolt 10 is inserted with the 90 flattened portions 15 uppermost, as in Fig. 6, and afterward turned half-way around to bring said flattened portions downward, as in Fig. 4, it exerts an eccentric tightening action tending to bind the parts firmly together. Preferably a groove 16 is provided in the extremity of the bolt to receive the edge walls of the aperture in the bail 6 and secure the clamping-bolt against withdrawal, as shown in Fig. 4.

95 For filling the reservoir or tank 2 with oil or such other liquid as may be employed an

exteriorly-threaded nipple 17 is provided, upon which a cap 18 is screwed when oil is not being poured in. Within the nipple 17 and upon one side wall of the same is mounted a vertical tube 19, which opens at its lower end 20 within the receptacle a little to one side of the nipple and is thus adapted to vent said reservoir as the oil is poured in.

The bottom or floor 3 of the reservoir is provided at its center with a pin-hole or perforation 21 for the escape of oil. In practice one such perforation has been found sufficient, but obviously I might, if desired, employ any number. Beneath the said floor 3 is a depending flange 22, which extends continuously around the pin-hole 21 at a distance therefrom and inclosing a long oblong space disposed centrally of the brush-back, as shown in Fig. 2. This flange is preferably formed by bending down the edge of a centrally-apertured floor-section 23, which is soldered to, and thus becomes a part of, the main floor 3 of the tank or reservoir, but obviously may be constructed in any other suitable manner.

Coming now to the brush proper, this comprises a wooden block or back 24, in which are inserted tufts 25 26, as is common in the art of brush-making. A middle longitudinal row of said tufts, as 26, are of absorbent material, and the top of the brush is centrally recessed or hollowed out, as at 27, to expose the tops of said absorbent tufts. In said recess 27, upon the floor thereof, is laid a pad 28, of absorbent material, preferably felt, and the said recess 27 is of such area or size that the flange 22 of the oil-reservoir sets into it and its edges press down into the absorbent cushion 28. Oil is thus supplied from the reservoir to the absorbent cushion 28 within the said flange 22 and from thence taken by the absorbent tufts 26 through capillary attraction. The flange 22 prevents escape of oil outside of where it is needed, and to further guarantee against any leakage I arrange an absorbent tuft 29 at each end of the brush outside of the said flange 22, so as to keep the felt 27 dry. By this means of distributing oil to the absorbent tufts the supply is regulated to each and such exacting care need not be employed in drawing said tufts to secure them of exactly the same fullness, so that their capacities are the same, which is necessary when tufts come in direct contact with oil.

For venting the chamber above the absorbent felt 28 a small passage or channel 30 extends through the brush-back 24, terminating at the base of an absorbent tuft. The pores of the felt provide extensions of the passage 30 in the wooden block. By the construction thus described it will be understood that when the tufts or bristle portion of the brush becomes worn the brush proper can be removed from the oil-reservoir and

handle and a new one applied. Furthermore, the back piece or block 24 of the one which has been removed can be redrawn with new tufts or bristles, so that there is no waste whatever.

Having thus described the invention, what I claim as new is—

1. The combination of a brush head or block having tufts drawn therein and having a recess or chamber in its top exposing the inner ends of a portion of said tufts, an absorbent pad in said recess, and a distributing reservoir adapted to supply oil to said pad, said reservoir having a depending flange which enters said recess and engages the pad, substantially as set forth.

2. The combination of a brush head or block having tufts therein and having a recess at its back exposing the inner ends of a portion of said tufts, an absorbent pad in said recess, an oil-storage reservoir upon the said brush head or block having a perforated bottom adapted to regulate the supply of oil to said pad, and having a depending flange formed continuously around the perforation in the bottom, and adapted to engage said pad, and means for fastening said brush-head and reservoir together.

3. The combination of a brush head or block longitudinally recessed at its back, tufts in said brush head or block a portion of which are open at their bases to said recess, an absorbent pad in the bottom of said recess means for holding said pad at the bottom of the recess, an oil-reservoir upon the said brush head or block having a port leading to said recess, and means for fastening said brush head and reservoir together.

4. The combination of a brush head or block having tufts drawn therein and being recessed at its back to expose the inner ends of a portion of said tufts, an absorbent pad in said recess, an oil-storage reservoir having a depending bottom flange projecting into the said recess against the said pad and having discharge means within the space inclosed by said flange, and means for fastening said brush head or block and the oil-reservoir together.

5. The combination of a brush head or block having tufts drawn therein and being recessed at its back to expose the inner ends of a portion of said tufts, an absorbent pad in said recess, an oil-storage reservoir having a depending bottom flange projecting into the said recess against the said pad and having a discharge perforation within the space inclosed by said flange, and means for fastening said brush head or block and the oil-reservoir together.

6. The combination of a brush head or block having tufts drawn therein and being recessed at its back to expose the inner ends of a portion of said tufts, an absorbent pad in said recess, an oil-storage reservoir having

its bottom edges forming a depending skirt or flange, an annular false bottom having its inner edges bent downward to form a flange adapted to engage said absorbent pad, the 5 said reservoir having bottom discharge-ports in the space inclosed by the said inner flange, and means for fastening said brush head or block and the oil-reservoir together.

7. The combination of a brush head or 10 block having a row of absorbent tufts drawn therein and being longitudinally recessed at its back to expose the inner ends of said tufts, an absorbent pad in said recess, an oil-storage reservoir having a depending bottom flange 15 projecting into said recess and engaging the said pad inside of the outer end tufts of said row, said reservoir having bottom discharge means within the said flange, and means for fastening said brush head or block and the 20 oil-reservoir together.

8. The combination with a transversely-apertured brush-block, an oil-reservoir mounted upon said brush proper and having 25 a skirt or flange extending down over the said head or block, and a transverse bail engaging the reservoir and having ends lying at the sides of the brush and being perforated in alinement with the said aperture of the head or block, of a fastening-bolt with a cylindrical shank portion adapted to lie in said 30 aperture and eccentric portions adapted to lie in the said perforations of the bail ends.

9. The combination with a transversely-apertured brush-block, an oil-reservoir 35 mounted upon said brush proper and having

a skirt or flange extending down over the said head or block, and a transverse bail engaging the said reservoir and having ends lying at the sides of the brush and being perforated in alinement with the said aperture of 40 the head or block, of a fastening-bolt with a cylindrical shank portion adapted to lie in said aperture and flattened portions adapted to lie in the said perforations of the said bail ends.

10. In a brush of the character described, a brush back or block having absorbent tufts in the bottom thereof and a recess at the top, an absorbent pad in said recess, the said pad and brush head or block having a vent-passage therethrough which opens at the bottom of the head or block adjacent to an absorbent tuft, and oil supply and distributing means upon the top of said head or block. 45

11. In a brush, the combination with a recessed block having absorbent bristle tufts extending from the outside into the recess, a porous pad arranged in the recess of said block, and a reservoir seated on said block and having a flange extending into the recess 50 and against said pad and a perforation in its bottom through which fluid may pass to said pad, substantially as set forth.

In testimony that I claim the foregoing I have hereunto set my hand this 30th day of 65 March, 1905.

JOHN WESLEY FERGUSON.
